UNITED STATES PATENT OFFICE.

HARALD J. VENNES, OF NEW YORK, N. Y., ASSIGNOR TO WESTERN ELECTRIC COMPANY, INCORPORATED, OF NEW YORK, N. Y., A CORPORATION OF NEW YORK.

CURRENT-WAVE TRANSMISSION.

Application filed December 7, 1921. Serial No. 520,695.

This invention relates to the transmission of currents of different frequencies, and more particularly to systems in which currents of different frequencies are impressed 5 simultaneously but independently upon the same circuit, such as, for instance, in multiplex signaling. The invention comprises a simplified circuit arrangement for associating a number of different current sources 10 with a common line, whereby currents having different characteristics are conveyed from said sources to said line without interference and in an efficient manner and whereby there is no reaction between the line 15 and the current sources.

Heretofore, for example, as indicated in United States Patents No. 1,313,483, August 19, 1919, of R. A. Heising, and No. 1,445,141, February 13, 1923, of B. W. Kendall it has been the practice to connect current generators of different frequency to a common line through an amplifier for each such generator and a selective circuit between each amplifier and the line. This necessitates the use of as many amplifiers as there are generators and means that each selective circuit must carry the amplified current and each amplifier must provide for the losses in the selective circuit due to the 30 amplified currents.

According to this invention one amplifier suffices for all the generators and this results in considerable saving of amplifiers, especially in systems carrying, for example, 30 or 40 transmissions in each direction. Also in the system according to this invention, the selective circuits carry the generated but not the amplified currents, so that the losses incurred in these portions of the circuit 40 are considerably reduced. Further, the provision of a unilateral device between the line and the individual selective circuits in the transmitting and receiving circuits, insures against any reaction between these circuits 45 and the line due to their reactive characteristics.

In the drawing, a carrier current telegraph system is shown, in which the separation between the transmitted and received 50 currents is effected by the use of wave filters. A Morse line arranged for full duplex operation with the carrier terminal station is also shown.

Referring to the drawing, a common 55 transmission line 1 is connected to the Morse

line 30 by a transmitting circuit and a receiving circuit, parts of which circuits are common to a plurality of channels and parts of which are individual to this channel. The common part of the transmitting circuit 60 comprises the wave filter 33 and the amplifier 34. The common part of the receiving circuit comprises the wave filter 35 and the amplifier 36.

The wave filters 33 and 35 are each adapted to pass a different group of frequencies, each one passing those frequencies which are characteristic of the individual channels to which they are connected. These filters are of the general type described in Patent No. 1,227,113, May 22, 1917 to G. A. Campbell. As shown, the filter 33 is a low pass filter, while filter 35 is a high pass filter. The amplifiers 34 and 36 may be of any suitable design, but are preferably electron discharge 70 devices of well-known construction, and will not be described in further detail.

For an individual transmitting channel an oscillator O_1 , which is a well-known design, supplies energy to a loop tuned circuit 80 37 through the transformer 38; the loop tuned circuit 37 being connected to the common transmitting circuit through the transformer 39. Other individual transmitting circuits may be connected to the common 85 circuit by means of other tuned circuits as indicated at 31.

On the receiving side an individual detector D_1 is connected to the common receiving circuit by means of a transformer 40 and 90 loop tuned circuit 41. The detector D_1 controls the receiving relay 42, which in turn controls the application of positive or negative potentials to the Morse line 30 from batteries 43 and 44, respectively. Such impulses do not affect the transmitting oscillator O_1 through the Morse receiving relay 45 because of the well-known Morse duplex bridge arrangement in which the Morse line 30 is balanced by the artificial line AL . 100 Other receiving circuits may be connected to the common receiving circuit by means of other detectors which may be connected to terminals such as 32.

Morse impulses incoming over the Morse 105 line 30 actuate relay 45 to short circuit the feed-back connection of the oscillator O_1 and so control the output of oscillations to the common line.

It is to be understood, of course, that there 110

are cooperating channels at the distant end of the common line 1. By the arrangement shown, full duplex operation can be carried on between the Morse line 30 and the corresponding Morse line at the distant station. In the above arrangement no balancing networks are required for the common transmission line 1. The filters 33 and 35 are designed to pass any desired range of frequencies and their design is independent of the reactive characteristics of the common line 1. Since the amplifiers 34 and 36 are unilateral devices, the reactive effects of the tuned transmitting and receiving channels are effectively isolated from the common line 1.

While the particular generators, transmitters and receivers illustrated and described are for telegraph transmission, it is obvious that the invention is adaptable generally to transmission of currents of different frequencies for the selective operation of any desired mechanism. For example, carrier currents, modulated in accordance with any desired kind of signal, such as speech, may be transmitted by providing the suitable transmitters and receivers, such, for instance, as a microphone transmitter and a telephone receiver. It is obvious also that transmitting and receiving antennae may be substituted for the line.

While the invention has been illustrated and described with reference to a particular system, it is to be understood that it is not to be limited to that specific system, either as to the circuit arrangements as a whole, or to the particular details, but only by the scope of the appended claims.

What is claimed is:

40 1. In a multiplex carrier wave transmission system, a plurality of oscillators furnishing waves of respectively different fre-

quency, each such oscillator having a tuned circuit for determining the frequency of the waves generated, a common collecting circuit, individual selective circuits coupling said oscillators to said common collecting circuit, a transmission line, a band filter directly connected to said transmission line, said filter being connected between said collecting circuit and said line and having a transmission range broad enough to include the frequencies furnished by all of said oscillators, and a single unilateral amplifying circuit connected between said filter and said common collecting circuit, whereby said oscillators are effectively isolated from the reactive effects of said filter and line.

2. A line for the transmission of currents in both directions thereover, a plurality of sources of currents of different frequencies, a plurality of individually tuned transmitting circuits respectively connected directly to said sources of current, a collecting circuit directly connected to each of said tuned transmitting circuits, a plurality of individually tuned receiving circuits tuned to frequencies different from those of the transmitting circuits, a circuit common to said tuned receiving circuits, a pair of wave filters connected in parallel with each other and directly to the transmission line, said filters being adapted respectively to transmit the transmitted and received frequencies, and a unilateral transmitting device connected in series with each of said filters, said transmitting devices being respectively connected to the collecting transmitting circuit and to the circuit common to the tuned receiving circuits.

In witness whereof, I hereunto subscribe my name this 28th day of November, A. D., 1921.

HARALD J. VENNES.
